SHOE SHIELD

Jay Rose, Brooklyn, N. Y.

Application January 8, 1936, Serial No. 58,054

9 Claims. (Cl. 36—70)

This invention relates to improvements in shoe attachments, and more particularly to a shoe clamp shield or protector.

I am aware that various types of shoe vamp protectors have appeared upon the market for attachment to the forward edge of the shoe vamp for lessening the pressure of the vamp edge against the instep and stocking of the wearer, and which are constructed of celluloid or like composition material. Due to the inherent characteristics of the material from which such protectors are constructed, the protectors do not maintain their original shape when subjected to pressure and use for they are lacking in resiliency sufficient to enable them to remain in clamped position upon the shoe vamp, and which in time results in displacement or accidental loss. It is therefore one of the main objects of this invention to construct the body of the vamp shield or protector of celluloid or like composition and attach thereto metal spring clips which provide a constant tension to positively effect clamping engagement with the shoe vamp under all conditions and during the life of the shield 25 to properly hold the shield in position and prevent accidental loss.

A further object of the invention is the provision of a combined shoe vamp shield which is simple and inexpensive of construction, easy 30 to apply and maintain upon the shoe vamp, which is capable of long use and assures comfort and ease to the foot of the wearer.

With these and other objects in view, the invention resides in certain novel construction, 35 combination and arrangement of parts, the essential features of which are hereinafter fully described, are particularly pointed out in the appended claims, and are illustrated in the accompanying drawing, in which:

40 Figure 1 is a side elevational view of a lady's pump style shoe with my invention in use thereon.

Figure 2 is an enlarged vertical sectional view 45 through the vamp of the shoe equipped with the invention.

Figure 3 is a perspective view of the invention per se.

Figure 4 is a vertical sectional view on the line 4—4 of Figure 3.

50 Figure 5 is a detail perspective view of one of the metal spring clips per se.

Figure 6 is a perspective view of a modified form of my invention.

Referring to the drawing by reference characters, the numeral 10 designates the preferred

form of my improved vamp shield in its entirety, which includes a shield body 11 constructed of a single piece of material such as celluloid or like composition and which has a curvature substantially that of the upper front edge of the 5 vamp 12 of a lady's pump style shoe 13. The curvature of the body 11 extends lengthwise of the same and one of the marginal edges thereof is curled to provide a hook portion 14. The bill or terminal edge of the hook portion terminates 10 in an outwardly extending lip or flange 15 which is disposed at an angle with respect to the adjacent portion of the body 11 to provide a wedge shaped mouth or entrance 16 to the inside of the hook portion and which facilitates the easy insertion of the shield into position upon the vamp edge of a shoe.

The inherent characteristic of the celluloid or similar composition from which the body 11 is constructed is insufficient to provide the desired 20 resiliency for firmly retaining the shield in position upon the vamp of a shoe, therefore, for adding the required resiliency, I provide resilient metal spring clips 18, one of which is shown in its natural position in Figure 5 of the drawing. 25

Each spring clip 18 is formed from a single piece of flat spring steel bent into a coil, the inner end terminating in an inwardly extending angular flange 19 and the outer edge terminating in an inwardly extending angular flange 20. The 30 clips 18 are respectively received in recesses 21 provided in the outer side of the coiled portion of the body member, and are disposed flush therewith. The flange 19 of each clip enters a slot or deeper recess 22 provided in the shield 35 at the juncture of the flange 15 with the curled portion, whereas the flange 20 enters a similar slot or keeper recess 23 in the body adjacent the restricted entrance to the hook portion 14. It is necessary to flex the coiled clips outwardly to 40 seat the same in their respective recesses which imparts an inward pressure at the restricted entrance to the hook or curled portion to normally set up a clamping action between the body portion 11 and the rounded edge between the flange 45 15 and the hook portion 14. In the drawing, three clips have been shown, one arranged centrally of the celluloid body, and the other two adjacent the respective ends thereof, to provide a sufficient spring tension along the length of 50 the curled portion of the shield. That portion of the clips 18 extending about the rounded portion of the shield body are tempered to provide the desired flexibility and resiliency.

In use, the vamp shield is applied to the front 55

of the vamp of the shoe 13, the same being usually formed with a bead or French edge 24. The walls forming the restricted entrance to the curled or hook portion are spread apart as the hook portion is engaged with the bead to enable the bead to enter and be engaged by the hook portion 14, as best seen in Figure 2 of the drawing. When in this position, the body portion 11 underlies the vamp and when the wearer's foot 10 is inserted into the shoe, the body portion is held flat against the vamp, thus lessening the pressure of the vamp edge upon the instep of the foot of the wearer. Any likelihood of the shifting or 15 accidental disengagement of the shield from the vamp edge is prevented by reason of the constant clamping action produced by the spring clips 18.

In Figure 1 of the drawing at the rear of the shoe, I have illustrated a heel protector or shield 31 which is constructed similar to the vamp shield 10 with the exception that the body portion 32 is longer in order to extend from the bottom of the shoe at the heel to the top when 20 hooked engagement with the French edge 24.

In Figure 6 of the drawing there is illustrated 25 a modified form of the invention in which the shield 33 is substantially U-shape in cross section and includes a body portion 34 of celluloid or like composition, a rolled or hook portion 35, an inwardly crimped portion 36 and an outer apron 30 37 extending in spaced relation to the body portion 34. Stamped from the apron 37 are stitch openings 38 to facilitate the sewing attachment of a vamp ornament in position upon the shield. Spring clips 18 similar to those hereinbefore 35 described are countersunk in the rounded or hook portion 35 and perform the same function as that herebefore described.

While I have shown and described what I consider to be the most practical embodiments of my 40 invention, I wish it to be understood that various changes in construction and form may be made as come within the scope of the appended claims.

Having thus described the invention, what I 45 claim as new and desire to secure by Letters Patent of the United States, is:—

1. A shoe shield comprising a thin flexible body shaped to conform to the shape of the edge of a shoe upper to which the shield is adapted to 50 be applied, a rolled portion formed integral with the upper edge of said body to engage over the edge of a shoe, metal spring clips countersunk in the exterior of the rolled portion to urge the free edge of the rolled portion toward said body, 55 and interlocking means between the ends of said clips and the rolled portion for securing said clips in position thereon.

2. An article of the class described comprising in combination, a stiff flexible shoe shield having 60 a body provided with a hook portion along one edge thereof, spaced countersinks provided in the exterior of the hook portion having recesses at the ends thereof, metal spring clips respectively seated in said countersinks, and angular inwardly extending flanges at the ends of said 65 spring clips and interlocking with the respective recesses.

3. A shoe shield comprising in combination, a 70 flexible substantially flat body having an integral hook portion along the top side thereof by which the shoe shield may be engaged with the upper

edge of a shoe, and resilient means acting upon the hook portion to increase the resiliency thereof to normally urge the terminal end of the same toward said flat body, to securely clamp the shoe shield in an adjusted position upon the upper edge 5 of a shoe.

4. A shoe shield comprising in combination, a flexible substantially flat body having an integral hook portion along the top side thereof, the body and hook portion being constructed of a composition of material whose inherent characteristic is insufficient to firmly cause the hook portion to 10 clampingly engage the upper edge of a shoe on which the shoe shield is adapted to be supported, and metal spring clips acting upon the hook portion to normally urge the terminal end of the same toward said flat body to securely clamp the shoe shield in an adjusted position upon the upper edge of a shoe.

5. A shoe shield comprising in combination, a 20 flexible substantially flat body having an integral hook portion along one side thereof, the body and hook portion being constructed of a composition of material whose inherent characteristic is insufficient to cause the hook portion to 25 firmly clamp upon the upper edge of a shoe on which the shoe shield is adapted to be supported, and metal spring clips countersunk within said hook portion and acting thereon to increase the resiliency thereof to normally urge the terminal 30 end of the same toward said flat body to securely clamp the shoe shield in an adjusted position upon the upper edge of a shoe.

6. A shoe shield comprising a relatively thin flexible flat body curved lengthwise to conform 35 to the shape of the upper edge of a shoe to which it is adapted to be applied, a rolled portion integral with and extending from the top edge of said body to engage over the upper edge of a shoe, spring means provided on and acting upon 40 said rolled portion to increase the resiliency of the same and to yieldably maintain its relative position with respect to said body, and a flared flange on the terminal end of said rolled portion.

7. A shoe shield comprising a thin flexible 45 substantially non-resilient flat body member provided with a hook portion at one side thereof for hooking engagement with the vamp edge of a shoe, resilient means acting upon said hook portion to increase the resiliency thereof to maintain its relative position with respect to said body member, and an angularly outwardly extending flange at the terminal end of the hook portion to facilitate snapping engagement of the hook portion with the vamp edge of a shoe.

8. A shoe shield comprising a flat body constructed of a substantially non-resilient composition of material, a rounded portion formed integral with and at the top of said body for hooking engagement with the upper edge of a shoe, 60 and spring means acting upon said rounded portion to maintain the shape thereof.

9. A shoe shield comprising a relatively thin flexible flat non-metallic body provided with a curled edge at the top side thereof for receiving 65 the upper edge of a shoe, and spring means provided on said curled portion for increasing the resiliency thereof for releasably clamping the shoe shield in a firm adjusted position upon the upper 70 edge of a shoe.

JAY ROSE.
